REVERSING GEARS FOR DIESEL ENGINES

George E. Ramstad, Milwaukee, Wis., assignor to
Nordberg Manufacturing Company, Milwaukee,
Wis., a corporation of Wisconsin

Application August 1, 1940, Serial No. 349,271

11 Claims. (Cl. 123—41)

This invention relates to reversing gears for Diesel engines, and particularly to the reversal and control of fuel injection in two cycle engines of the mechanical injection type.

In a pending application, Serial No. 258,777, filed February 27, 1939, issued June 3, 1941, as Patent Number 2,243,883 I describe a reversing gear for reversing not only the fuel pump mechanism, inlet and exhaust valves of a four cycle Diesel engine, but also for reversing the air starting mechanism. The whole mechanism is so interrelated, and is provided with such interlocks, that a single controller is movable from the neutral or stop position in two opposite directions for reverse directions of operation. There is thus a forward range of motion and a reverse range of motion of the controller. Each of these ranges is subdivided into three sub-ranges. Counted in order from the stop position, each first sub-range is one in which the reversing movement for the various valve gears takes place, the second is an air starting range in which the engine is put into motion by compressed air, and the third is a fuel control range within which the starting air is cut off and the fuel feed is controlled, the feed increasing with displacement of the controller from neutral or stop position.

The present invention has to do with fuel injection only, and though the device is suited for use as the fuel injecting mechanism in the general control combination above defined, the novel features have to do solely with fuel control, and, hence, will be discussed on that basis. The invention permits use of the gear of my prior application with two cycle mechanical injection engines.

I have determined that with a two cycle mechanical injection Diesel engine, the time of injection should be varied in relation to engine speed, for very much the same reasons that the time of ignition is varied in relation to engine speed in internal combustion engines operating on the Otto cycle.

The present invention produces a simple means for displacing the fuel cam shaft of a two cycle Diesel engine, angularly with respect to its drive, so that a single set of fuel cams may be set alternatively for forward and for reverse running. This primary adjustment is effected by means of a rack which engages a gear associated with the cam shaft drive. A reversing motor moves this rack full stroke between a forward running position and a reverse running position. In order to modify the lead or timing of the fuel injection,

the parts are so formed that the gear is displaceable in the direction of its axis and transversely of the rack, and such displacement causes angular displacement of the cam shaft. In the preferred arrangement, the rack is provided with teeth which are oblique with reference to the rack, and the gear is mounted on straight splines so that it may be shifted transversely relatively to the rack. Such shifting, because of the obliquity of the teeth, rotates the gear and hence the shaft, in proportion to the lateral displacement of the gear. Various alternative schemes will suggest themselves.

Movement of the rack between forward and reverse position entails movement of a secondary member which is connected through a variable stroke linkage with the gear displacing means in such a way that the motion of the secondary member moves the aforesaid gear laterally, more or less, depending on the adjustment of the linkage. The adjustment of the linkage might be effected manually, but for best results it is effected by a servo-motor under the control of a governor responsive to engine speed. It is not necessary or even desirable that such servo-motor develop force sufficient to shift the linkage while the cams are actuating the fuel pump. By limiting the force developed by the servo-motor, the adjustment may be caused to be intermittent, occurring when the cam shaft is lightly loaded. This reduces wear. In this discussion, the term "lead" is used to define the crank angle between the start of injection and the dead point.

Thus, the reversal of the engine is characterized by two concurrent adjustments of the angular position of the cam shaft relatively to the crank shaft. The first or basic adjustment is of considerable range and establishes the fundamental conditions for reversal. The second is a compensatory lead varying adjustment and can be so arranged mechanically that it is either added to or subtracted from the primary adjustment, without any difference in the mechanical principle involved other than certain reversals of pitch. The algebraic sum is selected to produce the desired effect.

To illustrate, using figures for one practical embodiment, suppose that the cam shaft must be shifted through an angle 100° to shift from normal lead position running forward to normal lead position running in reverse, and suppose that the desired variation of lead from normal speed to low speed is 4° in each position of running. From this it follows that the maximum angular range of adjustment from minimum lead run-

ning forward to minimum lead running reverse is 108°. On this basis, the primary adjustment could be set to give an angle of adjustment of 108°, and the secondary adjustment could subtract from this 4° in each range from mid-position, in which case the setting for maximum or normal lead would involve a shift of only 100°.

I prefer, however, and illustrate for purposes of disclosure, an arrangement in which the primary adjustment displaces the crank shaft through an angle of 100°, and the lead varying adjustment produced by axial displacement of the gear adds 4° for minimum lead conditions to each direction of running, so that the extreme range of angular adjustment is 108°.

Because the two schemes are approximately equivalent and involve merely reversals of pitch, it is deemed necessary to illustrate only the preferred arrangement, in which the compensatory or lead adjustment is additive rather than subtractive.

While the lead adjustment could be made manually, the invention gives its greatest utility when the lead adjustment is made in response to engine speed by a governor. An important aspect is that the control of lead by the governor is precisely the same for both directions of running; i. e. the reversing gear introduces no disturbing factor as to the governor control. The particular form of the governor is not a feature of the invention and will not be developed in detail. It is desirable to use that type of governor in which the speed responsive device pilots a servo-motor and the motor develops the force necessary to shift the lead controlling linkage.

Again referring to a commercial embodiment of the invention, it has been found satisfactory to arrange the governor so that it sets the mechanism for normal lead at normal engine speed, and reduces the lead progressively to the minimum value at an engine speed of approximately 112 R. P. M. Below this speed, the minimum lead setting remains in effect, because a change of lead below this speed has no practical significance.

The invention will now be described with reference to the accompanying drawings, which are limited to the mechanism for changing the timing of fuel injection, omitting all air starting gear but showing means for varying the quantity of fuel injected. It should be understood, however, that mechanisms for accomplishing these purposes are well known and that the invention introduces no limitation on their use. In fact, it is contemplated that the invention will be incorporated in a complete reversing gear including mechanisms of the type mentioned.

In the drawings:

Figure 1 is a vertical section transverse to the crank shaft of a mechanical injection Diesel engine, taken on the axis of one of the cylinders of the engine and through the fuel pump which delivers fuel to that cylinder. The engine is shown set to run forward, and forward directions of motion of the various components are indicated by arrows. The reverse position of the cam for that cylinder is indicated in dotted lines.

Fig. 2 is a vertical axial section through the reversing motor and rack, with the lock mechanism, parts being shown in the up or forward running position, and a portion of the rack being broken away to reduce the length of the figure.

Fig. 3 is a horizontal section on the axis of the cam shaft, drawn on a larger scale than Fig. 1, and showing the reversing gear set in ahead po-

sition and with the secondary adjustment zero, so that there is maximum or normal lead.

Fig. 4 is a view similar to Fig. 3, showing ahead position with the minimum lead setting and showing, also, the planetary drive for the cam shaft and the cam shaft with the cam in the ahead position of Fig. 1.

NOTE.—With reference to Figs. 3 and 4, it should be observed that the right-hand end of each of these figures is toward the observer in Fig. 1.

Fig. 5 is a detail view of the axially shiftable gear.

Fig. 6 is a detail view of the back of the reversing rack.

Fig. 7 is a section on the line 7—7 of Fig. 4.

Fig. 8 is a section on the line 8—8 of Fig. 4; and

Fig. 9 is a section on the line 9—9 of Fig. 7.

Referring first to Fig. 1, 11 represents the crank case and 12 represents the jacketed cylinder of a Diesel engine. Only one cylinder is shown, but normally the engine would have a plurality of cylinders connected to a common crank shaft with fuel injection pumps operated by cams on a single cam shaft, hereinafter described.

The piston 13 is connected by the connecting rod 14 to a corresponding crank 15 on the main crank shaft 16. The cam shaft 17 turns at crank shaft speed, as will hereinafter be described, and is provided with fuel cams 18, one for each cylinder. The forward setting of the cam shaft is indicated in full lines in Fig. 1, and the reverse position of the cam for the illustrated crank angle is indicated in dotted lines.

A roller cam follower 19 coacts with the cam to reciprocate the fuel plunger 21 of a variable feed fuel pump of the type known in the art as a "Bosch" fuel pump. The plunger 21 works in a cylinder 22 and may be rotated about its longitudinal axis by a sleeve 23 which is splined to the plunger and which is rotated by the displacement of a rack 24. The end of the plunger has a spill-back port indicated generally at 25, so that the angular position to which the plunger is turned determines the amount of fuel delivered per stroke. The variable spill-back occurs at the end of fuel delivery, so that the start of delivery is timed by the cam and the duration of delivery is controlled by such angular position of plunger 21. The fuel oil is delivered through a check valve 26 and pipe 27 to a fuel injection nozzle 28 of known form. The present invention is concerned merely with the timing of reciprocation of the plunger 21.

The crank shaft 16 carries a pinion 31 and this drives a large gear 32 which is not fast on the shaft 17 but, on the contrary, is a ring gear on a cage 33 which rotates coaxially with the cam shaft 17. The cage 33 is the housing of a planetary transmission which is coaxial not only with the cam shaft 17, but with an axially aligned timing control shaft 34. The cage 33 carries a series of beveled planet pinions 35 which mesh with a beveled sun gear 36 fast on the control shaft 34 and with a driving gear 37 fast on the cam shaft 17. The ring gear 32 has twice the pitch diameter of the crank shaft pinion 31 and, consequently, the angular velocity of the cage 33 is half the angular velocity of the crank shaft, but since the sun gear 36 is at rest, except for the reversing adjustments hereinafter described, the driving gear 37 and the cam shaft 17 rotate at twice the angular velocity of the cage 33.

Consequently, the cam shaft turns at crank shaft speed, but in the opposite direction.

Remembering that reversal is to be effected by displacing the cam shaft 17 angularly with reference to the crank shaft 16, it will be apparent that for any desired angular adjustment of the shaft 17, an equal and opposite angular adjustment of the shaft 34 must be made.

The shaft 34 having been related to the components of the engine which are affected thereby, the discussion from now on will refer primarily to the control shaft 34. It may be remarked that no effort has been made to illustrate the bearings which support the cam shaft 17 or the crank shaft, because these features are conventional and do not enter into the invention.

As in my prior application, above identified, reversal is produced by admitting air to opposite ends of a pneumatic piston motor, the air supply being cut off and the motor vented as soon as it has completed its working stroke.

The air motor is shown in detail in Fig. 2. In this figure 41 represents the air cylinder and 42 represents a motion controlling check cylinder that is separated therefrom by an interposed cylinder head 43. A piston 44 in the cylinder 41 is connected by a rod 45 with a check piston 46 in the cylinder 42. The lower end of the rod 45 extends beyond the cylinder 42 and is connected to a rack 47. The two working spaces in the cylinder 42 are connected by a pipe 48 with adjustable throttling needle valve 49. The working spaces are kept charged with oil under pressure by a branch pipe 51 which leads from a portion of the force feed lubricating system of the engine, a check valve 52 being interposed. The piston 46, therefore, merely prevents unduly rapid reversing motion.

To move the piston 44 and, consequently, the rack 47 to forward setting, which is the one shown in Fig. 2, air is admitted to the pipe 53 until the shift is completed and then pipe 53 is vented. For reverse shifting, air is admitted to the pipe 54 until the shift is completed, and then the pipe 54 is vented. The admission and venting functions are controlled by a maneuvering gear functionally similar to that forming the subject matter of my prior application, and not here involved.

Some means to latch the rack 47 in its two extreme positions are necessary and are embodied in a latching motor enclosed in the housing 55. Housing 55 takes the form of a differential or shouldered cylinder in which works a combined latch piston and valve 56, also shouldered as shown. A coil compression spring 57 urges the piston to the right, so that a latch nose 58 will engage beneath a latch shoulder 59 on the back of the rack 47 when the rack is in its upward or ahead position, and will engage behind a companion shoulder 61 when the rack is in its reverse position.

Leading from the housing 55 at the side opposite the connections 53 and 54, and slightly offset axially therefrom, are two pipe connections. The first, 63, leads to the lower end of the cylinder 41, and the second, 64, leads to the upper end of the same cylinder. In the latching position of the piston 56, these connections communicate with exhaust ports 65 and 66 in the piston 56, so that both working spaces in cylinder 41 are then vented to atmosphere by way of atmospheric port 67.

When air under pressure is admitted to the pipe 53, the piston 56 moves outward so that the 75

exhaust ports 65 and 66 move out of register. At such time, the outward movement of the piston connects pipe 53 with pipe 63, and pipe 54 with pipe 64. Consequently, the piston 44 is moved upward full stroke, the space above the piston 44 being exhausted through the pipe 54. When pressure fluid is admitted to the pipe 54, the reverse or downward motion takes place. At the end of the traverse and upon venting of the pipe 53 or 54, whichever was under pressure, the latch reengages.

The apparatus shown in Fig. 2 is simply a full stroke reversing motor with a fluid pressure latch which engages to hold the rack at the limit of motion after it has arrived at such limit. Various mechanisms of this type are known and equivalents may be substituted. In fact, any full stroke motor which will remain in its full stroke position at both limits of traverse could be used. The sole object is to move the rack full stroke between two limiting positions and retain it in the final limiting position. The upward position is the ahead setting of the reversing gear, and the lower position is the reverse setting.

25 In Fig. 6, the back of the rack is illustrated. The latch shoulder 59 is shown. The cam slot 68 which coacts with a follower 69, shown in Figs. 3 and 4, is a part of the interlock of my prior application, which assures that the reversing motor 30 moves full stroke before the reversing air is cut off. The cam slot 68 and follower 69 are not a part of the present invention and are here illustrated merely to indicate the possibility of interconnection with the maneuvering mechanism of my prior application. No claim to such mechanism is made in the present application.

The rack 47, as best shown in Fig. 8, has oblique teeth, and meshes with a spirally toothed gear 71 which is mounted on straight splines 70 40 on the shaft 34. It is simpler to form the rack with inclined teeth and the gear 71 with spiral teeth than it would be to make the splines 70 spiral. Hence, the construction illustrated is adopted, but the basic idea underlying the mechanism is that axial displacement of the gear 71 across the face of the rack 47 shall entail limited rotation of the shaft 34 assuming a fixed position for the rack. Any arrangement which would give this result is within the broad inventive concept and it is not essential that the spiral pitch be limited to the periphery as contradistinguished from the hub of the gear.

The outer end of the shaft 34, that is the left-hand end as viewed in Figs. 3, 4 and 8, is counterbored to receive an axially shiftable plunger 72. Swivelled in this plunger is a cylindrical block 73. The swivel connection is produced by the use of the small axial stem 74 which extends through a closely fitting bore in the plunger 72 and is held by a nut 75. The cylindrical block 73 is connected with the gear 71 by a cross-pin 76 which is held in place by the screw plugs 77 which are threaded into the gear 71 (see Fig. 9). The cross-pin 76 is flat in cross section, as best shown in Figs. 5, 8 and 9, and the threaded counterbores for the plugs 77 occur in inactive areas of the gear 71 from which the teeth are omitted. The maximum angle of motion of the gear 71 is of the order of 108°, so that the omission of a portion of the teeth at diametrically opposite points is practicable.

The counterbored portion of the shaft 34 is longitudinally slotted as indicated at 78 to afford clearance for the pin, but the torsional reaction

between the gear and the shaft is taken up by the splines 70 and not by the pin 76. Similarly, as best shown in Fig. 7, the plunger 72 is arcuately slotted as indicated at 79, to permit free angular motion of the pin 76. Thus, the only duty imposed on the pin is to shift the gear 71 in the direction of the axis of the shaft 34.

The outer end of the plunger 72 is slotted or bifurcated so that it affords two parallel lugs or extensions 81. These are each pinned on aligned axes 82 to one end of a corresponding one of a pair of longitudinally channeled spaced links 83. The other ends of these links are pinned on aligned axes 84 to a bifurcated yoke 85. The construction is such that the two links 83 are parallel at all times, swinging in unison so that they are, in effect, a single link. However, for ease of assembly, it is convenient to use two distinct links so connected that they move as one.

Each link has a longitudinal channel-like guideway 86 in which is slideable a fulcrum block 87. The two fulcrum blocks are pivoted on concentric axes 88 to a slider 89 which is guided in ways 91 to move at right angles to the axis of the shaft 34. At the inner limit of motion, the pivots 88 are coaxial with the pivots 82, and under this condition, regardless of the position of the pivots 84, the gear 71 is in its mid-position (see Fig. 3).

The slider 89 is connected by a link 92 with the controlling element of a governor mechanism 93 which is responsive to engine speed. So far as is material to the present invention, the governor mechanism is such that when the engine speed is normal, the parts assume the position shown in Fig. 3, in which the pivots 88 align with the pivots 82. As engine speed is reduced from normal, the slider 89 is shifted progressively to the position shown in Fig. 4, which is the low speed position. This position is assumed at a chosen minimum engine speed and all speeds below that minimum. In one engine constructed according to the invention, this minimum speed was of the order of 112 R. P. M. but the minimum is a matter of choice. Because the load on this governor is substantial, the governor should be of that known type in which the member 92 is shifted by a servo-motor in response to the indication of a speed responsive device. Since such governors are well known in the art, detailed illustration is not necessary.

The yoke 85 is pivoted at 94 to some part which moves a definite distance in a path parallel with the axis of shaft 34 during the full traverse of the rack 47. In the preferred embodiment, the pivot 94 is carried by a threaded member which is traversed in a direction parallel with the axis of the shaft 34 by a nut which rotates through a definite angle as the result of the displacement of the rack 47 through its full traverse.

Thus, the threaded member is shown at 95 and is provided with multiple right hand quick pitch threads, as clearly shown at 96. The nut 97 has companion internal threads 98 and is mounted to turn in bearings 99 formed in a part of the housing mechanism. The nut is provided with spiral teeth 101 which mesh with the spiral teeth on the gear 71, it being understood that the axis of the nut 97 is parallel with the axis of the shaft 34. It will require only a moment's reflection to appreciate that while the nut 97 is turned by the motion of the rack 47, it is unaffected by axial displacement of the gear 71, for the pitch of the spiral threads is such that the

gear 71 may be displaced axially while the nut 97 and the rack 47 both remain at rest.

Operation

The operation of the device in motion from the position shown in the drawings, which is forward running position, to reverse running position will now be traced.

To bring about this action air is admitted to the pipe 54 until the piston 44 moves downward its full traverse. The first effect is to disengage the latch 58 and upon venting of the pipe 54, the latch reengages. It is unnecessary to discuss the action of the interlock operated by the follower 69 and assuring full traverse before the air is cut off.

Assuming that the engine is at rest, the governor will position the slider 89 as shown in Fig. 4. As the rack 47 moves downward its full traverse, it will rotate the gear 71 and will also rotate the nut 97. The amount that the nut 97 rotates is directly proportional to the traverse of the rack, but the amount that the gear 71 rotates is the combined effect of rotation by the rack and displacement of the gear 71 full stroke to the right as an incident to the displacement of the threaded member 95 full stroke to the left. This reverses the inclination of the links 83 and forces the plunger 72 inward relatively to shaft 34. Consequently, the cam shaft 17 and cams 18 are displaced the maximum angle, here assumed to be 108°. When the engine operates and as its speed rises above 112 R. P. M., the governor moves slider 89 progressively until pivots 88 and 82 align when normal speed is attained. By such motion, the gear 71 will be restored to its mid-position (Fig. 3), establishing normal lead conditions.

Reduced to its simplest terms, the transverse of the rack imparts a definite angular rotation to the gear 71. At the same time it displaces the pivot 84 a definite distance. The effect of the displacement of the pivot 84 is to reverse the inclination of the links 83. The governor 93 effects the lead adjustment which must be in opposite senses for opposite directions of rotation, the desired reversal of sense being produced by the reversal of inclination of the links 83. The lead adjustment is effected solely by axial displacement of the gear 71.

While the particular arrangement shown is simple to manufacture and precise in operation, modifications within the broad scope of the invention are possible, and are contemplated.

In the first place, various modifications of the spiral arrangement by which axial displacement of the gear 71 causes rotation of the shaft 34 while the rack remains at rest are obviously possible. The one illustrated is selected because it is the simplest to manufacture.

It has also been suggested that the device can be arranged for a subtractive rather than for an additive effect of the lead adjustment. This would, for example, involve reversal of the slope of the teeth on rack 47 and gear 71 and appropriate change of the stroke of rack 47 on the diameter of gear 71, to modify the extent of rotation of that gear imparted by the reversing traverse of the rack alone.

I claim:

1. The combination of an engine of the fuel injection type having a crank shaft, a cam shaft provided with fuel injection cams and fuel injecting means operated by said cams; a drive train from the crank shaft to the cam shaft in-

cluding a controlling member which when rotated changes the angular relationship between the cam shaft and the crank shaft to establish forward and reverse running conditions as to the timing of fuel injection, and also to modify the lead of such injection; a reversing member shiftable full stroke between a forward running position and a reverse running position; a driving connection between said reversing member and said controlling member through which full stroke motion of the reversing member rotates the controlling member sufficiently to establish selectively said reverse running conditions, said driving connections including a displaceable component so arranged that its displacement rotates said controlling member through a lead adjusting range; a reversible motion transmitting mechanism, connected with said reversing member so as to be reversed by full stroke motion thereof, and connected with said displaceable component to actuate the same; and a lead adjusting device connected to actuate said reversible motion transmitting mechanism, and through it to actuate said displaceable component in relatively reverse senses in the forward and reverse positions of said reversing member.

2. The combination defined in claim 1 in which the reversible motion transmitting mechanism comprises a sliding block linkage including an oblique link and a sliding block serving as a fulcrum therefor, the reversing member being connected to reverse the obliquity of the link and the lead adjusting device comprises a speed responsive governor arranged to shift the sliding block.

3. The combination of an engine of the fuel injection type having a crank shaft, a cam shaft provided with fuel injection cams, and fuel injecting means operated by said cams; a drive train from the crank shaft to the cam shaft including a controlling member which when rotated changes the angular relationship between the cam shaft and the crank shaft to establish forward and reverse running conditions as to the timing of fuel injection; a toothed actuator shiftable full stroke between two limiting positions, one of which is a forward and the other a reverse setting; a gear unit meshed with said toothed actuator and in driving relation with said controlling member, said gear unit comprising an axially displaceable component whose displacement changes the angular position of the controlling member relatively to the position of the toothed actuator through a lead adjusting range; a member moved by said toothed actuator to two distinct positions by the shift of the actuator between its two limiting positions; a reversible motion-transmitting mechanism arranged to be reversely set by the shift of the last named member and connected to move said axially displaceable component; and shiftable lead controlling means arranged to actuate said axially displaceable component through said motion transmitting mechanism, the imparted motion being reversed by reversal of the motion transmitting mechanism.

4. The combination of an engine of the fuel injection type having a crank shaft, a cam shaft provided with fuel injection cams, and fuel injecting means operated by said cams; a drive train from the crank shaft to the cam shaft including a controlling member which when rotated changes the angular relationship between the cam shaft and the crank shaft to establish

forward and reverse running conditions as to the timing of fuel injection; a toothed actuator shiftable full stroke between two limiting positions, one of which is a forward and the other a reverse setting; a gear unit meshed with said toothed actuator and in driving relation with said controlling member, said gear unit comprising an axially displaceable component whose displacement changes the angular position of the controlling member relatively to the position of the toothed actuator through a lead adjusting range; a member moved by said toothed actuator to two distinct positions by the shift of the actuator between its two limiting positions;

5. The combination defined in claim 4 in which a reversible motion-transmitting mechanism arranged to be reversely set by the shift of the last named member and connected to move said axially displaceable component; shiftable lead controlling means arranged to actuate said lead controlling means.
6. The combination of an engine of the fuel injection type having a crank shaft, a cam shaft provided with fuel injection cams, and fuel injecting means operated by said cams; a drive train from the crank shaft to the cam shaft including a controlling member which when rotated changes the angular relationship between the cam shaft and the crank shaft to establish forward and reverse running conditions as to the timing of fuel injection; a toothed actuator shiftable full stroke between two limiting positions, one of which is a forward and the other a reverse setting; a gear unit meshed with said toothed actuator and in driving relation with said controlling member, said gear unit comprising an axially displaceable component whose displacement changes the angular position of the controlling member relatively to the position of the toothed actuator through a lead adjusting range; a member moved by said toothed actuator to two distinct positions by the shift of the actuator between its two limiting positions; a reversible motion-transmitting mechanism arranged to be reversely set by the shift of the last named member and connected to move said axially displaceable component; shiftable lead controlling means arranged to actuate said lead controlling means.

7. The combination defined in claim 4 in which the governor is so arranged as to shift said lead controlling means progressively between full engine speed and a low limiting speed, and to maintain said lead constant at a chosen minimum value at all speeds below said minimum speed.

8. The combination of an engine of the fuel injection type having a crank shaft, a cam shaft provided with fuel injection cams, and fuel injecting means operated by said cams; a drive train from the crank shaft to the cam shaft including a controlling member which when rotated changes the angular relationship between the cam shaft and the crank shaft to establish forward and reverse running conditions as to the timing of fuel injection; a toothed actuator shiftable full stroke between two limiting positions, one of which is a forward and the other a reverse setting; a gear splined to said controlling member and having teeth engaging the teeth of said toothed actuator, the forms of the teeth and of the spline being so correlated that axial displacement of the gear in opposite directions from normal midposition produces rotary adjustment of the controlling member through opposite lead adjusting ranges; a member moved by the shift of said toothed actuator to two distinct positions; a reversible motion transmitting device reversely set by shift of the last named member and connected to move said gear axially; and lead controlling means shiftable to impart motion to said motion transmitting device, the imparted motion being reversed by reversal of the motion transmitting device.

9. The combination defined in claim 6 in which the toothed actuator has oblique teeth and the splined gear which meshes therewith has spiral teeth.

10. The combination defined in claim 6 in which the member moved by the shift of the toothed actuator to two distinct positions is a second gear meshing with said splined gear.

11. The combination of an engine of the fuel injection type having a crank shaft, a cam shaft provided with fuel injection cams, and fuel injecting means operated by said cams; a drive train from the crank shaft to the cam shaft including a planetary train, one element of which is connected with the cam shaft, another element

of which is driven by the crank shaft, and a third element of which is relatively fixed, but rotatable to change the angular relationship between the cam shaft and the crank shaft, both to establish forward and reverse running conditions as to the timing of fuel injection and to modify the lead of fuel injection; a toothed actuator shiftable full stroke between two limiting positions, one of which is a forward and the other a reverse setting; a gear splined to said third element of the planetary train and having teeth engaging the teeth of said toothed actuator, the forms of the teeth and of the spline being so correlated that axial displacement of the gear in opposite directions produces lead modifying angular adjustment of the third element of the planetary train; a member operatively connected with said toothed actuator to be shifted to two distinct positions by the shift of the latter between its two limiting positions; a reversible motion transmitting device reversely set by shift of the last named member and connected to move said gear axially; lead controlling means shiftable to impart motion to said motion transmitting device, the imparted motion being reversed by the reverse settings of the motion transmitting device; and means for actuating said lead controlling means.

10. The combination defined in claim 9 in which the reversible motion transmitting device comprises an oblique link and a coating sliding block, the member shifted by the toothed actu-

ator serving in its two positions to establish relatively reverse oblique settings of the link, and the means for actuating the lead controlling means is connected to shift the block.

- 5 11. The combination of an engine of the fuel injection type having a crank shaft, a cam shaft provided with fuel injection cams and fuel injecting means operated by said cams; a drive train from the crank shaft to the cam shaft
10 including a controlling member which when rotated changes the angular relationship between the cam shaft and the crank shaft to establish forward and reverse running conditions as to the timing of fuel injection, and also to modify
15 the lead of such injection; a reversing motor shiftable full stroke between a forward running position and a reverse running position; two individually operable driving connections between said reversing motor and said controlling member. one of said connections being a direct connection through which the reversing motor turns said controlling member through a range sufficient to effect reversal of timing relation and the other being a motion reversing connection
20 comprising a shiftable fulcrum member, a link fulcrumed thereon and connected to transmit motion to said controlling member and means whereby the reversing motor reverses the obliquity of the link relatively to the direction of shift of the fulcrum member; and lead controlling means for shifting said fulcrum member.

GEORGE E. RAMSTAD.
